UNITED STATES PATENT OFFICE.

BERT W. TRUSCOTT, OF CLEVELAND, OHIO, ASSIGNOR, BY MESNE ASSIGNMENTS, TO VENEER BARREL MACHINE COMPANY, OF CHICAGO, ILLINOIS, A CORPORATION.

GRIPPING DEVICE FOR DOUBLE-STAVE-VENEER-BARREL MACHINES.

SPECIFICATION forming part of Letters Patent No. 739,363, dated September 22, 1903.

Application filed March 11, 1903. Serial No. 147,276. (No model.)

To all whom it may concern:

Be it known that I, BERT W. TRUSCOTT, a citizen of the United States, and a resident of Cleveland, county of Cuyahoga, State of Ohio, **5** have invented certain new and useful Improvements in Gripping Devices for Double-Stave-Veneer-Barrel Machines, of which I hereby declare the following to be a full, clear, and exact description, such as will enable others skilled in the art to which it appertains to **10** make and use the same.

My invention relates to improvements in machinery for making veneer barrels from a plurality of veneer pieces; and the especial **15** objects of the invention are to provide means for securely binding the veneer pieces upon the barrel and for gripping also the inner extremities of the hoops, so that as the drum of the machine revolves the veneer pieces will **20** be compressed by the hoops, and a complete barrel can thus readily be formed from various veneer pieces instead of from one large integral piece of veneer as formerly.

I accomplish my objects by means of the **25** internal springs designed to be projected at the will of the operator and adapted to extend over and compress the inner extremities of the hoops upon the first piece of veneer introduced into the machine.

30 My invention further consists in the combination and arrangement of the various parts, as hereinafter described, shown in the accompanying drawings, and specifically pointed out in the claims.

35 In the accompanying drawings, Figure 1 is a perspective view of a machine adapted to accomplish my objects. Fig. 2 is an end view of the drum. Fig. 3 is a similar view showing the compression-roller down and in the **40** act of raising the extremities of the springs so that the hoops can be introduced thereunder.

In the views, 1 is the veneer-coiling drum, similar to those now in use. 2 is the shaft **45** therefor, and 3 the operating-gear.

4 is a roller longitudinally mounted on a bearing 5, which reciprocates vertically in guides 6 and is manipulated by means of the

lever 7 and the weight 8. This roller is of less width than the slot or narrow opening 9, running longitudinally of the drum 1.

The springs 10 are curved to conform to the circle of the drum-cylinder and are attached to the bars 11, which are diametrically placed within the cylinder and sleeved at 12 over the **55** shaft. A bar 13 connects the outer extremities of the diametrical bars, and a handle secured thereto serves to throw the springs within or without the cylinder, as required.

In operation a piece of veneer **r** being placed **60** within the slot underneath the springs, as shown in Fig. 2, the roller is then brought down upon the springs directly over the opening between the body of the drum and the edge of the collapsible portion 14 thereof. **65** The depression of the springs in the opening against the edge of the collapsible portion of the drum causes the free extremities of the springs to rise, as seen in Fig. 3, so that the ends of the hoops **H** can be inserted **70** underneath them. The drum being then rotated, the hoops fed through guides 15 are held rigidly by the springs, which at once grip the hoops closely as soon as they are released. Two men usually attend one machine, one in **75** the rear nailing the veneer strips and hoops together as the drum rotates.

By means of this device barrels can be formed of narrow or scrap pieces of veneer, and thus more economically than from single **80** pieces of veneer.

Having described my invention, what I claim as new, and desire to secure by Letters Patent, is—

85 1. In combination, a veneer-coiling drum provided with a collapsible portion separated from one edge of the drum by an open slot, curved springs within the drum concentric therewith, rotatably supported upon a common support upon the drum-shaft, a handle **90** upon the support for the springs by means of which they can be rotated so as to project beyond the edge of the drum over the open slot and slightly over the edge of the said collapsible portion, upon which they find a bearing, **95** and means for raising the outer extremities

of the springs so that the barrel-hoops can be inserted thereunder, substantially as described.

2. In combination, in a veneer-barrel machine, a veneer-coiling drum provided with a collapsible portion separated from one edge of the drum by an open slot, means for securing the first of a succession of veneer pieces to the drum and for simultaneously binding the extremities of the hoops thereon, consisting of curved springs within and concentric with the drum, a common support for the springs rotatably secured to the drum-shaft, means for rotating the support to project the extremities of the springs beyond the edge of the drum across the open slot and over the

edge of the collapsible portion of the drum, upon which they bear closely, and means for raising the outer extremities of the springs so that the veneer and hoops can be inserted 20 thereunder while the springs lie across the slot, consisting of a vertically-moving roller adapted to press down the springs over the open slot between the edges of the drum, substantially as described. 25

In testimony whereof I hereunto set my hand this 28th day of February, 1903.

BERT W. TRUSCOTT.
